UNITED STATES PATENT OFFICE.

THURMAN J. BIXLER, OF HUTCHINSON, KANSAS.

TAG-HOLDER FOR SHIPPING BOXES OR CASES.

1,231,988.

Specification of Letters Patent.

Patented July 3, 1917.

Application filed February 5, 1917. Serial No. 146,686.

To all whom it may concern:

Be it known that I, THURMAN J. BIXLER, a citizen of the United States, residing at Hutchinson, in the county of Reno and State 5 of Kansas, have invented certain new and useful Improvements in Tag-Holders for Shipping Boxes or Cases, of which the following is a specification, reference being had therein to the accompanying drawing.

10 This invention relates to improvements in shipping boxes or crates, or particularly to a novel construction of shipping card or tag holder therefor.

15 Bottled soda, beer, mineral water and other liquids or substances are commonly shipped in cases or boxes from a point of supply to a point of destination, and it has been common heretofore to apply shipping cards in various ways to such boxes or cases.

20 The common practice is to simply write the name and address of the addressee upon a card or tag and to tack or either fasten such card or tag to some suitable portion of the box. As a result of this practice, the box is 25 mutilated, the tag very often lost or misplaced, and the addressee is subjected to the trouble of removing the original tag and applying another return tag in shipping the box or case, after being emptied, to the original point. Cards or shipping tags thus 30 affixed are also exposed to the weather, with resultant disadvantages.

The object of my invention is to provide 35 a card or tag holder which forms a complementary part of the box itself, and which is formed in or upon one of the walls of the box in such a manner as to expose one side of the shipping card or tag to view, the construction being such that the tag may be 40 easily and conveniently removed as required and will be held against loss or displacement by the lid or cover of the box which holds it confined in position.

45 A further object of the invention is to provide a construction of holder which admits of the use of a card or tag bearing upon one side the name and address of the shipper and adapted to receive on its reverse side the name and address of the shippee or party to whom the filled box is to be shipped, so that by simply reversing the position of the card it will serve as an address card for both directions of shipment.

55 The invention consists of the features of construction, combination and arrangement of parts, hereinafter fully described and

claimed, reference being had to the accompanying drawing, in which:—

Figure 1 is a fragmentary top plan view, with parts broken away, of a shipping box 60 or case embodying my invention.

Fig. 2 is a fragmentary end elevation of the same.

Fig. 3 is a vertical section on the line 3—3 of Fig. 2. 65

Figs. 4 and 5 are views of the opposite sides of the shipping card or tag.

The box or case 1 is constructed, as usual, of wood or other suitable material, and as shown is of oblong or rectangular form, 70 comprising a bottom wall 2, front and back walls 3 and 4, end walls 5, and a hinge lid or cover 6, which lid or cover is hinged, as shown at 7, to the back wall and is adapted to rest when in closed position upon the 75 upper edges of the back, front and end walls and to be secured in closed position in any suitable manner. Suitable cleats 8, one of which is shown, may be employed at the corners of the box for strengthening purposes. 80

In carrying my invention into practice, I provide a card or tag holder which is a component part of one of the end walls 5. The end wall 5 shown in the present 85 instance is illustrated as comprising a body portion 9, composed of a board or strip, which rests upon the bottom wall and extends between the front and rear walls and projects upwardly a distance less than the 90 full height of the body of the case, leaving a space between the same which is filled by a superposed board or strip 10. This board or strip may be secured in position in any preferred manner and extends between the 95 front and rear walls, rests at its base upon the upper edge of the board 9 and has its upper edge flush with the upper edges of the remaining vertical walls of the case.

The strip 10 is provided with a vertical 10 slot 11 extending between its top and bottom edges and communicating on its outer side with a display opening 12. This slot 11 forms a pocket or chamber to receive the shipping card or tag 13 and is of just 105 sufficient size to admit of the card being loosely held in position so that it may be conveniently applied and removed. One of the sides of the card is provided with a suitable form 14 to receive the name of the 110 person to whom the filled case is to be shipped, while the reverse side of the card

is provided with a return address form 15, which may be the name of the manufacturer, jobber or dealer shipping the goods, and to whom the crate or case is to be returned 5 after the contents have been emptied or used.

It will be observed that the upper end of the slot or pocket 11 opens through the upper edge of the end wall 5, so that when 10 the lid or cover 6 is in open position the shipping card or tag may be readily inserted or removed, while when the lid or cover is in closed position it will over-lie the slot or holder and confine the card against accidental loss or misplacement. The face of 15 the card to be used will be exposed through the opening 12, and it will thus be understood that the shipper will place the card in position with the face 14, bearing the desired address, facing the opening 12 so 20 as to be exposed therethrough, while in returning the box or case to the shipper the card is simply reversed in the holder to expose the address face 15. It will thus be seen that the invention provides a shipping 25 card or tag holder which forms a part of the box itself, which provides for the convenient display of the card while protecting it from loss or injury, and which admits of 30 the reversal of the card, so that it may be employed as a shipping tag for shipment of the case in both directions. The construction described admits of a box or case being furnished which but slightly exceeds in cost 35 the cost of ordinary boxes or cases, while

affording the conveniences stated and obviating the objectional and customary practice of tacking shipping cards to the outer surface of the box, as will be readily understood.

Having thus described my invention, I claim:

In a card or tag holder for boxes, shipping cases or the like, the combination of a box body having bottom, side and end walls, 45 one of said end walls comprising a body portion terminating below the body of the other walls, and a superposed strip filling the space between said body portion and the horizontal plane of the said other walls, 50 said strip being provided with a vertical longitudinal passage extending between the top and bottom edges thereof and forming a pocket opened at its top and closed at its base by the body portion of the wall, and 55 having in its outer side a display opening extending through the outer wall of the pocket and communicating therewith, a cover adapted when in closed position to rest upon the side edges of the side and 60 end walls and to close the mouth of the pocket, and a card loosely fitting within said pocket and having reverse faces for containing address matter.

In testimony whereof I hereunto affix my 65 signature in the presence of two witnesses.

THURMAN J. BIXLER.
